UNITED STATES PATENT OFFICE.

ISABEL LIKENS GATES, OF WASHINGTON, DISTRICT OF COLUMBIA.

GARMENT SUPPORT.

Application filed March 5, 1923. Serial No. 622,946.

To all whom it may concern:

Be it known that I, ISABEL LIKENS GATES, a citizen of the United States, residing at Washington, District of Columbia, have invented certain new and useful Improvements in Garment Supports, of which the following is a specification.

The invention relates to camisoles, brassières, ladies' lingerie, dresses or similar articles of apparel which are supported or hung from the shoulders of the wearer, and more particularly to the provision of means for supporting a garment of this character in such a manner as to obviate the tendency of such supporting means to slide off from the shoulders of the wearer and at the same time having said means contracting or gathering certain parts of said garment.

A further object of the invention is the provision of a supporting means comprising a strap, tape or ribbon formed preferably from a single continuous piece, and which can be very readily applied or removed when the garment is to be laundered or a new string utilized and which will be attractive in appearance.

Illustrative embodiments of the invention are shown in the accompanying drawing, in which

Fig. 1 is a perspective view of the garment on a wearer's body with the supporting means in place.

Figs. 2 and 3 are plan views of two forms of the invention with the garment omitted.

Fig. 4 is a sectional view of the upper part of the garment of Fig. 1 showing the manner of introducing the supporting means into the top of the garment.

Fig. 5 is a cross-section on the line 5—5 of Fig. 4.

Fig. 6 is a plan view of a modified form of garment and supporting means removed from the body.

Figs. 7, 8, 9 and 10 are plan views of different forms of the invention with the garment omitted.

As shown in Figs. 1, 2 and 3 the upper garment portion 3 is provided with a tubular portion 4 extending completely around the top of the garment tho it may be omitted at the arm-pit portions and is formed by hemming the material as at 5 and then stitching the material together as at 6'.

In Figs. 1, 2 and 3, the device comprises a strap, ribbon, tape or cord having an end portion 6 tied, stitched or otherwise fastened

to the top front portion of the garment as at 7. A portion 8 of the ribbon is then passed rearwardly over the shoulder and enters the tubular portion 4 thru an opening 9 positioned approximately opposite the point 7. A portion 10 of the ribbon is then threaded thru the portion 4 for a distance along the back of the garment until it reaches a point adjacent the opposite shoulder where it leaves the tubular portion thru an opening similar to 9 and is passed forwardly over the last mentioned shoulder forming the strap portion 11. The ribbon then enters the front tubular portion as at 12 and has a portion 13 extending across the front of the garment to a point 14 where it leaves the tubular portion and extends rearwardly over the shoulder to form the portion 15. The ribbon again enters the tubular portion 4 at the back of the garment approximately opposite the point 14 and is threaded across the back of the garment forming the portion 16 until it reaches a point adjacent the opposite shoulder where it leaves the tubular portion and is extended over the shoulder forming the ribbon portion 17. The end 18 is then fastened as by tying or stitching to the front of the garment as at 19 which is similar to the fastening 7.

From the drawing it will be seen that Fig. 3 differs from Fig. 2 in that instead of having the ends 6 and 18 fastened to the garment as at 7 and 19 respectively they may enter the tubular portion 4 at approximately the points 7 and 19 and threaded thru the same toward the center front of the garment forming the ribbon portions 20 and 21. The ends of the ribbon may then leave the tubular portion at the front and center of the garment and there be tied in a bow or knot.

As shown in Fig. 4 a loop 22 may be used in order to keep different portions of the ribbon separated from each other at a point where they enter the tubular portion. And tho the drawing shows a plurality of ribbon portions extending thru the same tubular portion nevertheless it should be understood that a plurality of tubular portions may be formed as by spaced rows of stitching and each adapted to receive a single ribbon.

As shown in Fig. 6 the upper garment portion 30 has a highly decorative edging 31 which is provided with a plurality of openings and passageways 32 to which the

ribbon is adapted to be slidably threaded or tied tho it may be omitted at the armpit portions.

In the form of the invention shown in Figs. 6 and 7 the end 33 of the ribbon is tied or otherwise fastened to the edging 31 as at 34. The ribbon is then passed rearwardly and diagonally up over the shoulder to a point 35 on the rear edging thereby forming the ribbon portion 36; then the ribbon is threaded thru a section of the rear edging 37 forming the ribbon portion 38; the ribbon is then extended forwardly and diagonally up over the shoulder to a point 39 on the front edging forming the ribbon portion 40; the ribbon is then threaded across and thru the front edging to the point 41 forming the portion 42. From the point 41 the ribbon continues rearwardly and diagonally up over the shoulder to the point 43 on the rear edging forming the portion 44; then it is threaded thru a section of the rear edging to the point 45 from where it extends forwardly and diagonally up over the shoulder to the point 46 on the front edging forming respectively the ribbon portions 47 and 48 respectively. At the point 46 the ribbon end 49 is tied and bowed or otherwise fastened. It will be noted that the form shown in Fig. 8 differs from that of Fig. 7 only in that the ends 33 and 49 instead of being fastened at the points 34 and 46 continue into the front edging and are threaded there thru toward each other until they reach the front and center of the garment where they may be tied to each other and bowed and form the ribbon portions 50 and 51.

The form of the invention shown in Fig. 9 is similar to that shown in Fig. 8 tho in Fig. 9 the portions 36 and 48 are continuously connected by the portion 52 and do not each terminate in ends 33 and 49, while in Fig. 9 instead of having the continuous portion 42 the portions 53 and 54 are provided which terminate in the ends 55 and 56 respectively.

The supporting and contracting means shown in Fig. 10 does not have the shoulder strap portions crossing each other over the shoulders. In this figure two pairs of parallel shoulder strap portions 57—58 and 59—60 are provided. The portions 61 and 62 engage the upper edge of the garment similarly to 47 and 38 and the portions 63, 64 and 65 engage the upper edge of the garment similarly to 52, 53 and 54, respectively, while the ends 66 and 67 are adapted to be tied and bowed to each other.

It will of course be understood that in all cases the ribbon slidably engages the tops of the garments and that the forms shown in Figs. 7, 8, 9 and 10 may be used with the garment of Fig. 1 while the forms shown in Figs. 2 and 3 may be used with the garment of Fig. 6.

It is found that a strap formed of ribbon preferably continuous and positioned as described is very comfortable to wear and has no tendency to slip off the shoulders, thus relieving the wearer of the necessity of awkward, and embarrassing movements required to replace the ordinary form of suspension means in position.

A further advantage of this garment support consists in the fact that it avoids the tearing of the garment to which it is attached, it yields with the movements of the wearer and draws or contracts certain parts of the garment to the body.

Minor changes may be made in the physical embodiment of the invention without departing from its spirit.

I claim:

1. In combination with a garment adapted to encircle a wearer's body, a continuous support having a portion threaded thru and slidably engaging a portion of the garment and a plurality of portions adapted to extend over each of the wearer's shoulders with the arm-pit portions of said garment free of said support.

2. In combination with a garment adapted to encircle a wearer's body, a continuous support having a portion threaded thru and slidably engaging a portion of the garment, a plurality of portions adapted to extend over each of the wearer's shoulders, and a portion slidably engaging another portion of said garment with the arm-pit portions of said garment free of said support.

3. In combination with a garment having a front portion and a back portion, and adapted to encircle a wearer's body, a continuous support having a plurality of separated portions threaded thru and slidably engaging one of said garment portions, a portion threaded thru and slidably engaging the other of said garment portions and a plurality of portions adapted to extend over each of the wearer's shoulders with the arm-pit portions of said garment free of said support.

4. In combination with a garment having a front portion and a back portion and adapted to encircle a wearer's body, a continuous support having a plurality of separated portions threaded thru and slidably engaging one of said garment portions, a plurality of separated portions threaded thru and slidably engaging the other of said garment portions and a plurality of portions adapted to extend over each of the wearer's shoulders with the arm-pit portions of said garment free of said support.

5. In combination with a garment adapted to encircle a wearer's body, a continuous support having a plurality of portions threaded thru and slidably engaging a portion of said garment and a plurality of portions adapted to extend over each of the

wearer's shoulders with the arm-pit portions of said garment free of said support. 6. In combination with a garment having arm-pit sections, a front portion and a 5 back portion, a support having a portion threaded thru and slidably engaging one of said portions, a plurality of separated portions threaded thru and slidably engaging spaced apart portions of said other portion 10 with the middle portion of said other portion free of said support when the garment is in wearing position and portions adapted to extend over a wearer's shoulders.

7. In combination with a garment having arm-pit sections, a front portion and a back 15 portion, a support having a plurality of portions threaded thru and slidably engaging one of said portions, a plurality of separated portions threaded thru and slidably engaging spaced apart portions of said other portion 20 with the middle portion of said other portion free of said support when the garment is in wearing position and portions adapted to extend over a wearer's shoulders.

ISABEL LIKENS GATES.
